(57) **CLAIM**

The ornamental design for a bracket, as shown and described.

DESCRIPTION

FIG. 1 is a front, top, right perspective view of a bracket, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom, left perspective view thereof;

FIG. 9 is a front, top, right perspective view, showing the bracket in use with a horizontal column; and,

FIG. 10 is a front, top, right perspective view, showing the bracket in use with a vertical column.

The dashed broken lines in the drawing depict portions of the bracket that form no part of the claimed design.

The dot-dash lines in the drawing depict boundaries of the bracket that form no part of the claimed design. Specifically, regions surroundingly defined by the dashed broken lines and the dot-dash lines are no part of the claimed design.

Slanting surfaces of FIG. 1 and FIG. 2 surroundingly defined by the solid lines and the dot-dash lines have a plurality of nicks thereon that are shown in the dashed broken lines and that are no part of the claimed design.

The dot-dot-dash lines depict environment that forms no part of the claimed design.

1 Claim, 8 Drawing Sheets
